UNITED STATES PATENT OFFICE.

CHARLES SPAETH, OF CLEVELAND, OHIO, ASSIGNOR TO THE MARVEL EQUIPMENT COMPANY, OF CLEVELAND, OHIO, A CORPORATION OF OHIO.

DISPENSING PUMP.

Application filed February 28, 1924. Serial No. 695,640.

My invention relates to an improvement in a liquid measuring and dispensing device, particularly in a measuring pump for dispensing lubricating oils, and in general 5 my object is to provide a transparent oil column in connection with an open nozzle for the pump wherein a substantial body of oil may be constantly retained and displayed without drip from the nozzle when the pump 10 is inactive, and wherein the body of oil in the column may be visibly agitated by a jet of oil while the pump is active and a steady flow of oil is being dispensed.

The device is designed to permit a free 15 and uninterrupted discharge from the nozzle immediately upon operating the pump while constantly retaining a full head of oil on display in the glass column, and as constructed the device also stops the flow of oil 20 instantly without drip at the discharge mouth of the nozzle when pumping operations cease.

In the accompanying drawings, Fig. 1 is a side view of a dispensing pump embodying 25 my improvement. Fig. 2 is an enlarged sectional view of the nozzle and oil display column for the pump. Fig. 3 is a horizontal section on line 3—3 of Fig. 2.

The invention comprises a nozzle 2 having 30 a tapped intake 3 adapted to be screwed upon the discharge pipe 4 of a measuring and dispensing pump 5 of any suitable type or kind. In the present instance the pump contains a valved piston 6 which is recipro- 35 cated in a well known way by operating a crank handle 7. The oil is drawn from a container 8 into the barrel or cylinder of the pump upon the upward stroke of the piston while the oil above the piston is 40 being discharged, and a check valve 9 at the bottom of the pump prevents the oil from returning into container 8 upon the downward stroke of piston 6. As a result the pump head 10 and its discharge pipe 4 and 45 nozzle 2 are always full of oil, and an additional quantity of oil is also maintained in a glass tube 11 attached to and forming a display column above the nozzle in line with its vertical discharge spout 12. This 50 spout is open at its bottom and in constant open communication with tube 11 and the discharge side of the pump as indicated in Fig. 2, where it seemingly appears that the oil within the column would be drained completely from the column by gravity upon a

cessation of pumping operations. However this is not the result in practice, the present device being particularly constructed to utilize a small degree of vacuum within the column and the atmospheric pressure outside to hold the oil in suspension substantially the full height of the column when the pump is inactive. Thus, nozzle 2 embodies a horizontal wall 13 having separate sets of relatively small intake and outlet openings 60 14 and 15, respectively, of different diameters. A division wall 16 within nozzle 3 separates the intake side of the nozzle from the discharge side which is formed with a reduced extension into which a straight piece 65 of pipe of small diameter is tightly fitted to provide a small discharge spout 12. The relative areas of the intake and outlet openings 14 and 15, respectively, determine whether the column will remain full of oil 70 when the pump is inactive, and leakage and drip is also controlled thereby. The size of the intake openings 14 is also a factor in effecting the proper rate of flow of the incoming stream relatively to the outflow 75 through the smaller outlet openings 15, the diameter of the intake openings 14 preferably being such that the incoming oil will be jetted with considerable velocity into the column of oil within the glass tube so that 80 visible agitation of the oil occurs in filling the column initially and in subsequent dispensing operations when the column is full or nearly full. The smaller outlet openings 15 restrict the outflow of oil from the glass 85 tube but a rapid uniform uninterrupted stream of oil is discharged at the small spout 12 while the pump is being operated to jet oil into the column, and in this proceeding the oil level is higher on the intake side 90 of the column than on the outlet side as illustrated in Fig. 2. When pumping and jetting ceases the oil flow from the discharge spout 95 stops instantly and the column of oil within the glass tube remains at the same height 100 at about the level shown in the drawings and no leakage or drip occurs notwithstanding the outlets are open.

Satisfactory results as above stated may be obtained with a heavy oil by using a single inlet port 14 approximately nine thirty-seconds in diameter, or several smaller openings aggregating that area, providing the outlet port or ports 15 are about twenty per cent smaller. A series of small ports may be 105 110

used to increase the volume of discharge, but by making the ports small one or more fine streams of oil may be jetted into the column with sufficient velocity to agitate the body 5 of a heavy lubricating oil so that a large percentage of the air above the oil in the glass tube will be mixed with and absorbed by the oil jetted into the column and conveyed out of the tube and the volume of 10 compressed air in the tube reduced to a minimum, especially in filling the tube in the first instance or when empty. In this connection it will be understood that the jets of oil will shoot through the rising body of oil 15 and agitate it while it is flowing through the outlet ports 15 and in so doing convey a large percentage of the trapped air with the oil whereas, without such jetting of the oil a large volume of air within the tube will be 20 compressed and the tube will either be only partly filled or be under such pressure that it will escape and drip at the spout for some time after stopping pumping operations.

As shown nozzle 2 is provided with an annular enlargement and flange 18 surrounding a flat seat upon which a compressible ring gasket 19 is placed to seat the bottom edge of glass tube 11. The upper end edge of this tube is sealed by a similar gasket 20, and a flanged cap or cover 21 and a single tie rod 22 may be used to fasten the tube in place upon the nozzle. Tie rod 22 passes through a tapered opening 23 in the cap or cover, and suitable packing 24 may be compressed around the tie rod within this tapered opening by the enlargement or nut 25 when the tie rod is screw-connected to the nozzle.

I claim as my invention or discovery:

1. A liquid dispensing device comprising a discharge nozzle and a display tube for the liquid being dispensed, said nozzle having upwardly directed inlet ports of restricted area for said tube to jet a fine stream of oil upwardly into said tube, and said tube having outlet ports of capillary size with respect to said liquid.

2. A liquid dispensing device, comprising a discharge nozzle and a display column 50 through which the liquid may be forced and

held in suspension alternatively, the nozzle and the column having communicating inlet and outlet ports, said inlet ports being of restricted area and adapted to jet fine streams of oil forced into said nozzle into said column and the outlet ports being of capillary size with respect to said liquid and constantly open to the atmosphere.

3. A liquid dispensing pump, comprising a constantly open discharge nozzle and a transparent tube surmounting said nozzle and in constant open communication therewith by way of inlet and outlet openings of different size, said outlet opening being of capillary size with respect to the liquid to be dispensed and said inlet opening being vertically arranged and of about 20% larger size than said outlet opening to permit jetting of a fine stream of oil into said tube by force of the pump.

4. A liquid dispensing pump, comprising a delivery nozzle having a constantly open discharge spout, and a transparent tube surmounting said nozzle having small vertically arranged intake and capillary outlet ports in constant open communication with the intake and discharge sides of said nozzle, whereby a fine stream of liquid may be vertically jetted through the intake port into the tube to violently agitate the liquid so trapped therein in order to absorb the air above said liquid and convey said air with said liquid through said capillary outlet port during pumping operations.

5. An oil dispensing pump, comprising a delivery nozzle having a divided discharge chamber provided with a small vertically arranged intake opening and a plurality of capillary outlet ports, said vertically arranged small inlet port being adapted to jet a fine stream of liquid upwardly, and said capillary outlet ports being adapted to stop a flow of the liquid at normal pressure, a glass tube seated upon said nozzle in sealed surrounding position relatively to said ports, a cap enclosing and sealing the upper end of said tube and a tie rod uniting said cap with said nozzle.

In testimony whereof I affix my signature,
CHARLES SPAETH.
